H. L. GANTT,
SPARK ARRESTER FOR TOBACCO DRYING HOUSES.
APPLICATION FILED FEB. 11, 1921.

UNITED STATES PATENT OFFICE.

HENRY L. GANTT, OF ROSELAND, VIRGINIA.

SPARK-ARRESTER FOR TOBACCO-DRYING HOUSES.

1,383,927.

Specification of Letters Patent.

Patented July 5, 1921.

Application filed February 11, 1921. Serial No. 444,132.

To all whom it may concern:

Be it known that I, HENRY L. GANTT, a citizen of the United States, and a resident of Roseland, county of Nelson and State of Virginia, have invented certain new and useful Improvements in Spark-Arresters for Tobacco-Drying Houses, of which the following is a full and complete specification, reference being made therein to the appended drawings.

The proper curing and drying of tobacco depends upon the application for a continued space of time to the tobacco of uniform heat. The tobacco is customarily hung in the leaf in bunches depending from rods or sticks. A large number of these bunches of leaves are hung in spaced relationship each to the other within a barn or house in which the requisite heat may be applied to the drying tobacco while adequate means are provided for proper ventilation. The heat required to complete the drying process varies during the several stages carried out and toward the end of the operation is quite intense.

The heat for drying the tobacco may be supplied from sources external from the house and led into same by means of ducts or flues. In this manner the flues which are customarily made of sheet metal become quite hot and, unless shielded from contact with the partially dried tobacco may cause the latter to take fire.

Where reliance is had upon a blazing fire built upon the floor of the house and under the hanging tobacco bunches, there is even greater danger from fire which may be caused by the falling of the tobacco leaves or a stick carrying an amount of the tobacco into the fire. In the latter event the tobacco fragments will blaze up sufficiently high to carry sparks among the hanging bunches and set fire to the latter.

It is an object of my invention to provide means whereby the tobacco during the drying and curing operation may be subjected directly to the hot gases from an open fire without the danger of catching fire from the upwardly traveling sparks.

It will be apparent that the means provided by my invention to accomplish the above result will also insure the even distribution of heat rising from the fire and permeating the tobacco.

By means of my invention the burning of any portion of the tobacco, which may fall

from its support, is prevented and the risk of fire is minimized.

A form in which my invention may be carried out is illustrated in the accompanying drawing in which,

Figure 1 is an elevation showing the disposition of my spark arrester between the tobacco and the open fire,

Fig. 2 is a plan view of one of the units composing the spark arrester,

Fig. 3 is an end elevation of said unit, viewed from the right of Fig. 2, and

Fig. 4 is a section along the line 4-4 of Fig. 2.

The bunches of tobacco are supported loosely from the cross sticks 5 which latter are spaced each from the other. The cross sticks 5 are supported at their ends upon the tier poles 6. These tier poles extend from side to side of the drying house and are arranged in parallel pairs separated each from the other by a distance of approximately four feet.

The spark arrester consists of a plurality of units represented generally by the numeral 7. The number of units used is dependent upon the number of pairs of tier poles 6 which are provided in the house. A unit 7 is hung beneath each vertical row of tier poles.

The unit 7 of the spark arrester consists of a pair of frames 8 and 9. The lower frame 8 is rectangular and has the wire mesh 10 fastened to the frame as indicated. The upper surfaces of the longitudinal members of frame 8 carry the raised ribs 11 and 12 which form a parallel track. The frame member 9 has a corresponding groove in the lower surfaces of the longitudinal members. These grooves coöperate with the ribs 11 and 12 of the member 8 upon which the frame 9 is thus adapted to slide into and out of adjusted position. A wire mesh 13 is provided upon the upper surface of the member 9.

Extending from one cross bar of member 9 is a depending flap 14 which connects the wire mesh 13 of one member 9 with the wire mesh fabric 10 of the opposite frame member 8.

One side of the frame 8 carries two strap metal brackets 15 and 16. The lower ends of the straps 15 and 16 are bent inward as at 17 to form a hook resting in a groove cut in the lower surface of the frame 8. The upper ends of the straps 15 and 16 are turned in as at 18 and provided with an eye through

which a rod 19 is bolted. The rod 19 has a hook at its upper end by means of which it is suspended by the staple 20 to the tier pole 6. By the proper adjustment of the bolts 5 upon the screw threaded rod, the frame 8 may be maintained in horizontal position. The opposite side of frame 8 carries strap members 21 and 22 similarly equipped at their upper ends with the inturned portions 10 and rod 19. The lower end of the strap 22 is bifurcated and the ends upturned on opposite sides to provide hooks 23 and 24 similar in function to the hook 17. It will thus be evident that the frame 8 is suspended 15 ed an adjustable distance beneath the tier poles 7 and in a horizontal plane.

The frame member 9 carries a strap member 24 similar to strap 16, and a strap member 25 similar to the strap member 22. 20 These members are each supported by means of hooked rods 19 and staples 20 in a manner previously described. It will be apparent that the frame 9 is adapted to hang in practically the same horizontal plane as 25 the upper surface of frame 8 and may be adjusted over the latter to accommodate the width of the drying house.

As illustrated in Figs. 2 and 3, the unit 7 is equipped to occupy the end position in the 30 drying house with a side containing the brackets 15 and 16 and 24 contiguous to the end wall of the drying house. Any number of units 7 consisting of frames 8 and 9 may be attached to the free ends of brackets 35 21, 22 and 25, it being essential that brackets 21 and 22 be between each two frames 8 and that a bracket 25 be disposed between each two frames 9.

The frame 9 is drawn out from position 40 over frame 8 so that the opposite ends of the two frame members will be contiguous to the side walls of the drying house.

Arranged as above described, the fire screen or spark arrester constitutes a partition about 5 feet above the ground upon 45 which the fire is built and immediately beneath the hanging bundles of tobacco leaves. The metallic wire mesh fabric 10 and 13 serves the double purpose of arresting 50 sparks which may fly up from the fire and also of preventing falling material reaching the fire. As the sparks come in contact with the wire they are extinguished and rendered harmless. The wire mesh has the property 55 of maintaining a relatively cool temperature and does not become highly heated from the upwardly passing gases. Therefore, par-

ticles of leaves which fall upon the screen are not ignited but may remain safely until disposed of by the operator.

The flap 14 prevents sparks which may be arrested by the screen 12 from being carried by currents of air over to the material which may have fallen on screen 10.

It is found that a further advantage follows the use of the wire mesh 10 and 13 in that the heated gases are evenly distributed by their passage through the wire and that all of the bundles of tobacco are uniformly subjected to the heat.

While I have disclosed one preferred form of my invention, it will be apparent that many changes may be made in structural details without departing from the spirit of my invention as set forth in the claims, and that the device is adapted for use with various materials and treating agents, the application to the curing of tobacco being merely one preferred use.

What I claim is:

1. A spark arrester unit for the area of a drying chamber consisting of a plurality of elements each having a frame and a foraminous fabric thereon, means on one of said elements for receiving another of said elements 85 in an adjustable over-lapping relationship, and suspending means for said elements.

2. A spark arrester unit for the area of a drying chamber consisting of a plurality of elements each having a frame and a foraminous fabric thereon, means on one of said elements for receiving another of said elements in an adjustable over-lapping relationship, suspending means for said elements and a partition connecting the fabric portions of 95 the element.

3. A spark arrester for the area of a drying chamber consisting of a plurality of adjacent units, each unit consisting of a plurality of over-lapping elements permitting 100 the unrestricted ascent of heated gases, and common suspending means for adjacent units.

4. A spark arrester for the area of a drying chamber consisting of a plurality of adjacent units, each unit consisting of a plurality of over-lapping elements permitting 105 the unrestricted ascent of heated gases, hangers between adjacent units, said hangers having opposed members supporting 110 the adjacent units.

In testimony whereof, I have hereunto affixed my signature.

HENRY L. GANTT.
